UNITED STATES PATENT OFFICE.

LAWRENCE A. FLEMING, OF FAIRMONT, WEST VIRGINIA.

DESIGN FOR A PORTABLE REFRESHMENT BOOTH.

Application filed January 22, 1927. Serial No. 20,467. Term of patent 14 years.

To all whom it may concern:

Be it known that I, LAWRENCE A. FLEMING, a citizen of the United States, and a resident of Fairmont, county of Marion, and State of West Virginia, have invented a new, original, and ornamental Design for Portable Refreshment Booths, of which the following is a specification, reference being had to the accompanying drawing, forming part thereof.

Figure 1 is a perspective view of a port-

able refreshment both showing my new design,

Figure 2 is a top plan view thereof.

This structure constitutes an independent or complete article of manufacture, and is made and sold as such.

I claim:

The ornamental design for a portable refreshment booth, as shown.

L. A. FLEMING.
